INVENTOR,
Martin R. Donnallan

BY

Geo. P. Kimmel, ATTORNEY.

UNITED STATES PATENT OFFICE.

MARTIN ROBERT DONNALLAN, OF LONG BEACH, CALIFORNIA.

PUMP SCREEN.

Application filed July 23, 1923. Serial No. 653,394.

To all whom it may concern:

Be it known that I, MARTIN ROBERT DONNALLAN, a citizen of the United States, residing at Long Beach, in the county of Los Angeles and State of California, have invented certain new and useful Improvements in Pump Screens, of which the following is a specification.

This invention relates to a pump screen, 10 designed primarily for use in connection with mud pumps employed for the extraction of the formation which is necessarily attendant in oil well drilling operations, but it is to be understood, however, that a pump screen in accordance with this invention can be employed for any purposes wherein it is found applicable, and the invention has for its object to provide, in a manner as hereinafter set forth, a pump screen for 20 increasing the life of the valves, valve seats and inserts of, as well as preventing any retardation or interruption of the operation, of the pump by the elimination of the entrance of rock, gravel, wood chips, which 25 ordinarily would with the suction applied, enter in to the pump and cause thereby the clogging thereof, injury to the valves, as well as to the valve seats and inserts, and which further requires a constant taking 30 apart of the pump, the replacement of the valve and the valve seats, but more especially the valve seats and inserts.

A further object of the invention is to provide a pump screen, in a manner as 35 hereinafter referred to and for the purpose set forth, which is easily removable from the main shaft of the pump so that when obstructions have accumulated at the entrance to the screen, the latter may be removed 40 by one operation, and thoroughly cleaned and replaced.

Further objects of the invention are to provide, in a manner as hereinafter referred to, a pump screen for the purpose set forth, 45 which is simple in its construction and arrangement, strong, durable, capable of being quickly arranged in operative relation with respect to the pump and removed therefrom when occasion so requires, thoroughly 50 efficient and convenient in its use and comparatively inexpensive.

With the foregoing and other objects in view, the invention consists of the novel construction, combination and arrangement of 55 parts, as hereinafter more specifically described and illustrated in the accompanying

drawings, wherein is shown an embodiment of the invention, but it is to be understood that changes, variations and modifications can be resorted to which come within the 60 scope of the claims hereunto appended.

In the drawings wherein like reference characters denote corresponding parts throughout the several views:

Figure 1 is a sectional elevation of a portion of a pump, showing the adaptation therewith of a screen in accordance with this invention.

Figure 2 is a section on line 2—2, Figure 1.

Figure 3 is a top plan view of the screen element.

Figure 4 is a side elevation of the screen element.

Figure 5 is a side elevation of a modified 75 form of screen element.

Figure 6 is an elevation of one of the clamping members.

Referring to the drawings in detail, 1 denotes the main shaft of the pump and 80 which is adapted to have secured against the inlet end thereof a screen element in accordance with this invention.

The screen element as illustrated in Figures 1, 3 and 4 comprises a collar 2, formed with a pair of oppositely disposed laterally extending lugs 3, 4, arranged in the same plane and each provided with a vertically disposed opening 5 which has its lower end communicating with a semi-spherical recess with the wall thereof indicated at 6 and constituting a seat. The wall of the opening formed by the collar 2 is of two different diameters, and that portion of larger diameter is indicated at 7, and the portion of smaller diameter at 8. The portion 7 of greater diameter is of greater height than the portion 8 of smaller diameter. The providing of the wall of the opening formed by the collar of two different diameters provides a seat 9, which extends from the lower terminus of the portion 7 of greater diameter, and merges in the upper terminus of the portion 8 of smaller diameter.

Formed integral with the collar 2, as well as depending therefrom is a foraminous member of semi-spherical contour and which is indicated at 10. The diameter at the upper end of the member 10 is greater than the diameter of the opening formed by the collar 2. The member 10 is perforated

throughout, as indicated at 11, and the perforations are graduated in size from the base to the top of the member 10. The perforations 11 are circular in contour and with 5 the perforations of smaller diameter being positioned at the base of the member 10 and the perforations of greater diameter are arranged at the top of the member 10. The top of the member 10 surrounds the lower 10 end of the opening formed by the collar 2, and the inner face, at the top of the member 10, is spaced throughout from the portion 8 of smaller diameter of the opening formed by the collar 2.

15 The construction of the screen element shown in Figure 5 is similar to that shown in Figures 2, 3 and 4, but with this exception, that the semi-spherical member, indicated at 12, and which is formed integral 20 with and depends from the collar 2 is provided with rectangular perforations 13, in lieu of the circular perforations, but the perforations 13 are graduated as to size and with the smaller perforations at the base 25 of the member 12 and the larger perforations at the top thereof.

The main shaft 1 of the pump has its lower end extended into the opening formed by the collar 2, and with the lower edge of 30 said shaft 1 mounted against the seat 9, as shown in Figure 1. By this arrangement the collar 2 not only abuts against the shaft 1, but also overlaps the terminal portion thereof and when the collar 2 is mounted in 35 such position the inlet end of the shaft 1, is protected by the foraminous member 10 or 12, thereby preventing the entrance of rock, gravel or other débris to the pump.

The screen element is detachably connected 40 with the shaft 1, through the medium of a combined coupling and clamping device, and which includes a pair of coupling rods 14, 15, each having the lower end formed with a globular enlargement 16, positioned 45 against the seat 6 when the rods 14 and 15 are mounted in coupling position. The upper portion of the rod 14, as well as the rod 15, is peripherally threaded, as at 17 and carries an abutment nut 18, a washer 19 and 50 a clamping nut which may be of any suitable construction, but as shown by way of example, of the winged type and which is indicated at 20.

The combined coupling and clamping device further includes a pair of oppositely 55 extending semi-circular clamping members 21, 22, each having its inner face formed with tapering threads 23 for biting into the periphery of the shaft 1 so as to obtain 60 a firm hold thereon and to prevent slipping of the clamping members 21, 22, relative to the shaft 1. Each of the clamping members formed with a pair of oppositely extending laterally disposed flanges 24, 25, 65 and when the members 21, 22 are positioned

against the shaft 1, the flanges 24, 25 of one clamping member oppose the flanges 24, 25 of the other clamping member, but are spaced therefrom, in a manner as shown in Figure 2. Each flange 24, as well as each 70 flange 25, is provided with an opening 26 and when the clamping members 21, 22, are positioned against the shaft 1, the openings 26 of the flanges 24 oppose each other and the openings 26 of the flanges 25 oppose each other. When the clamping members 21, 22, are positioned against the shaft 1, the coupling rod 14 is extended upwardly 75 between the flanges 24 and the coupling rod 15 is extended up between the opposed flanges 25.

The combined coupling and clamping device further includes a pair of clamping bolts 27, 28, and each of which carries a securing nut 29. The bolt 27 extends through the openings 26 of the flanges 24, and the bolt 28 extends through the openings 26 of the flanges 25. The bolts 27 and 28 and nuts 29 are employed for securing the clamping members 21, 22 to the shaft 1, and the said clamping members 21, 22, are not removed from the shaft 1, when the screen element is disconnected from the shaft 1 for the purpose of cleaning such 80 element.

The coupling rods 14, 15, are secured to the flanges 24 and 25, for the purpose of maintaining the screen element against the end of the shaft 1, as shown in Figure 1, by the positioning of the nuts 18 against the lower edges of the flanges 24 and 25 and the further adjusting the nuts 20 and washers 19 on the rods 14 and 15, so that the washers 19 will be securely clamped against the upper edges of the flanges 24, 25, in a 100 manner as shown in Figure 1, whereby the screen element 10 will be fixedly secured in operative position with respect to the inlet end of the shaft 1.

The nuts 18 prevent the washers 19 from falling down on the rods 14, 15 into the mud when the screen element is disconnected from the shaft 1.

The spherical enlargements 16 at the lower ends of the rods 14, 15, in connection with the seat 6 provide fulcrums upon which the coupling rods can be shifted thereby facilitating the removal of said rods between the flanges 24, 25, when it is desired to disconnect the screen from the 110 lower end of the shaft 1.

Although the foraminous member 10 is of semi-spherical contour which is the preferred shape for said member, yet the same can be of conoidal shape if desired, and furthermore the perforations formed in said member 10 or 12 can also be of any shape desired, and although the preferred embodiment of the invention is as described 125 and illustrated, yet it is to be understood 130

that changes in the details of construction can be had which will fall within the light of the invention as claimed.

What I claim is:—

In testimony whereof, I affix my signature hereto.
